UNITED STATES PATENT OFFICE.

LLOYD BROWN, OF LOS ANGELES, CALIFORNIA, ASSIGNOR TO SILENT DRAMA SYNDICATE, A TRUSTEESHIP, LLOYD BROWN AND ALEXANDER GRAYDON, TRUSTEES.

MAGAZINE AND MAGAZINE ATTACHMENT FOR KINETOGRAPHS.

Application filed January 20, 1920. Serial No. 352,765.

To all whom it may concern:

Be it known that I, LLOYD BROWN, a citizen of the United States, residing at Los Angeles, in the county of Los Angeles, State 5 of California, have invented new and useful Improvements in Magazines and Magazine Attachments for Kinetographs, of which the following is a specification.

This invention relates to magazines for holding films for kinetographs and relates to means for mounting or attaching such magazines to the kinetograph; and although I explain a preferred form of magazine, and magazine attachment, particularly as applied to a camera, it will be understood that my magazine construction and attachment is not at all necessarily limited to cameras, but may be used in any situation in kinetograph mechanisms where it is applicable.

It is a general object of the invention to provide an effective and improved form of magazine; in which the film may be easily placed and which will fully protect the film; and to provide an improved attaching or 25 mounting means by which the opening for passage of the film from the magazine may be automatically opened as the magazine is attached to the camera. It is also an object to provide, in such a structure as here outlined, a simple and effective means for attaining the purposes of the invention.

The invention itself will be best understood from the following detailed description of a preferred form of mechanism embodying the invention, reference for this purpose being had to the accompanying drawings, in which—

Fig. 1 is a vertical longitudinal section of the improved film magazine; Fig. 2 is a section taken as indicated by line 2—2 on Fig. 1, and also taken as indicated by lines 2—2 on Figs. 4 and 5; Fig. 3 is a central vertical section taken as indicated by line 3—3 on Fig. 1 and as indicated also by lines 3—3 on Figs. 4 and 5; Fig. 4 is a bottom face view of the base of the magazines, said view being taken as indicated by line 4—4 on Fig. 3; and Fig. 5 is a plan view of the recess which receives the base of the magazine, said view being taken as indicated by line 5—5 on Fig. 3.

In the drawings the numeral 10 designates a circular case having a back wall 11 and a circular side wall 12. The front of 5 the case has a circular opening for inser-

tion and removal of reels of film, and this circular opening is closed by a circular cover plate 13, screw threaded at 14 into the opening, the cover plate making a light-tight joint with the case. The back wall 11 has a recess 15 therein for the passage of a driving pulley 17 on the reel shaft 18. The driving pulley, and its appurtenances, are protected against injury by the recess 15. The shaft 18 extends through the back wall 11 and also extends through the face plate 19; and inside the case it carries member 20, upon which the reel spool 21 is mounted. Member 20 has a pin 22 set through it and through the shaft 18; and the reel spool 21 is slipped over the member 20 and has slots 21^a which engage the pin 22. The reel spool (of soft wood) is pressed against knife blades 20^a on flange 20^c of member 20. Member 20 engages shaft 18 only near its end. A bearing sleeve 20^a surrounds the shaft; and member 20 runs on the bearing sleeve; both shaft 18 and member 20 being thereby given a long bearing and any possibility of binding being eliminated. 80 Sleeve 20^a is supported on a flange 20^b secured to plate 19. A flange 20^c on the end of member 20 bears against flange 20^b, forming an end thrust bearing for the shaft. Between pulley 17 and wall 11 there is a 85 disk or washer 25 pinned or keyed to the shaft to rotate therewith; and a spring washer or other suitable form of spring at 26, confined under screw-head 27, presses wheel 17 back against the washer. The proper amount of friction is thus engendered between the pulley 17 and the friction washer 25. The disk bearing at 20^b—20^c takes the end-thrust of spring 26.

Plate 19 is of some hard, smooth finished metal, say steel; with radiating ribs 19^a on its face. These ribs are polished smooth and form surfaces for the reel of film to run against. Plate 19 is set into the case as a separate piece because it is most easily formed as a separate piece and because the preferred material (aluminum) for the case does not serve well as a material for the anti-friction face plate.

The case 10 has a base at 30. This base is rectangular in plan (see Fig. 4) and is adapted to fit into the rectangular recess 31 in the wall 32 of the kinetograph. One end wall at 33 of this recess is an overhanging wall, and the end of the base 30 is adapted 110

to be slipped in under the overhanging wall, so that when the base is in the position shown in Figs. 2 and 3, that end of the base is held down by the overhanging wall. At 5 the other end of the recess the wall 34 is straight; so that the other end of the base may be set down into the recess. This other end of the base is then held in place by means of a screw 35 which screws up into 10 a bushing 36 set in the base 30. The base and the case are, in this particular instance, made of cast aluminum and it is therefore desirable to place a bushing 36 of brass or other suitable material in the cast aluminum 15 to carry the thread. The screw 35 has a large head 37 on its lower end. The screw projects through the wall 32 of the kinetograph mechanism, the head 37 being on the inside of the mechanism; and the screw is 20 yieldingly pressed upwardly by a spring 38 held in a small housing 39. The spring pressing the screw upwardly facilitates the screwing of the screw upwardly into the screw-threaded bushing 36; and at the same 25 time the spring allows the upper end of the screw 35 to be pushed downwardly when the magazine is first put in place so that the screw will be automatically set ready for manual manipulation when the parts are assembled.

It will be noted that both ends of the base 30 are similarly constructed; and in the other end of the base there is also the same screw-threaded bushing 36^a. This provision 30 is made so that the same magazine may be used either for the top or for the bottom of a camera mechanism in a situation where both magazines have their cover plate 13 turned toward the same side and where the 35 two screws 35 (the one for the upper magazine and the one for the lower magazine) are both at the same face of the camera.

The film F comes out of or goes into the magazine over a roller 45 and through a slot 45 formed between two blocks 46 and 47. Block 46 is stationary and is secured in the base in the position indicated; while block 47 is movable toward block 46. Block 47 has a large flat flange 48 which is movable in 50 a recess 49 in the bottom of the base. The flange 48 is held up against the bottom of the base by headed screws 50 which play in slots 51 in flange 48; and the flange 48, with its block 47 are pressed toward block 46 by 55 a suitable flat spring 52. Normally this spring 52 presses the block 47 toward the block 46 so as to tightly grip the film between the felt facings 46^a and 47^a of the two blocks. When, however, the magazine is 60 put into position as shown in Figs. 2 and 3, then the bevelled surfaces 53 of a pair of pins 54 entering a pair of apertures 55 in flange 48 press that flange and its block 47 back away from block 46 to a sufficient 65 extent to take the pressure off the film, yet

not to a sufficient extent to open up wide the slot between the two blocks. Thus, when the magazine is in place, then the opening between the two blocks is opened up sufficiently to allow the film to pass more or less 70 freely out of or into the magazine, and yet the space is not large enough to allow any appreciable filtering of light therethrough. The film also passes between two walls 60 upon entering the interior of the camera 75^a case. These walls are faced at 61 with felt or the like; and the bottom of the recess 31 is likewise faced with felt as shown at 62. The slot at 63, through which the film passes between the walls 60, is just 80 wide enough to allow free passage of the film without any substantial leakage of light.

At the end toward the opening 16, through which the driving means for pulley 15 pass 85 to the interior of the case and to the drive mechanism contained therein, light is prevented from entering between the ends of the blocks 47 and 46 by a plate 70 against which the ends of the blocks abut. The 90 other end of the slot between the blocks is of course protected by the wall 31^a of the recess 31.

Having described a preferred form of my 95 invention, I claim:

1. The combination of a kinetograph case having a magazine seat with a film passage therethrough, a film magazine having a film passage to register with the passage in said seat, a sliding member housed between said 100 magazine and case and forming a movable wall for said magazine film passage, means automatically to slide said member when said case and magazine are assembled and the film passages brought into registry, and means for fastening said magazine and case in 105 assembled position.

2. The combination of a kinetograph case having a recessed seat in its wall with a film passage therethrough, a film magazine 110 fitted to said recessed seat and having a film passage to register with the passage in said seat, a sliding block mounted in a recess between said magazine and seat and forming a movable wall for said magazine film passage, means to normally maintain said block in position to close said film passage, means automatically to slide said block and open said magazine film passage when said case and magazine are assembled, and means for 115 fastening said magazine and case in assembled position.

3. In combination with a kinetograph case, a film magazine, a relatively stationary block and a relatively movable block on 12 the magazine and between which the film passes, a spring normally moving the movable block toward the stationary block, and beveled pins carried by the kinetograph case and engaging the movable block to move it 13

away from the stationary block when the magazine is placed upon the case.

4. In combination, a kinetograph case having a wall with an exterior recess with an overhanging wall at one end, and with a film slot passing through the case wall from the recess, a film magazine having a base with an extended end adapted to fit under the overhanging recess wall and thereby be held in the recess, means for holding the other end of the base in the recess, the magazine having a film slot adapted to register with the film slot of the kinetograph case, one side of said magazine slot being formed by a movable block, and means to move said block to open the slot when the magazine base is placed in the recess; the second mentioned end of the magazine base being similar in formation to the first mentioned end, the said means for holding the second mentioned end of the base embodying interengaging means on that end of the base and in the kinetograph case wall, and the first mentioned end of the base having also such interengaging means, so that the magazine base may be secured in the recess in a position turned end for end.

5. In combination, a kinetograph case having a wall with an exterior recess with an overhanging wall at one end, and with a film slot passing through the case wall from the recess, a film magazine having a base with an extended end adapted to fit under the overhanging recess wall and thereby be held in the recess, means for holding the other end of the base in the recess, the magazine having a film slot adapted to register with the film slot of the kinetograph case, one side of said magazine slot being formed by a movable block, a spring normally pressing said block toward the other side of the slot to close the slot, said block having openings therein, and beveled pins projecting from the bottom of the recess and adapted to engage in said openings to press the block back against the spring.

6. In combination, a kinetograph case having a wall with an exterior recess with an overhanging wall at one end, and with a film slot passing through the case wall from the recess, a film magazine having a base with an extended end adapted to fit under the overhanging recess wall and thereby be held in the recess, means for holding the other end of the base in the recess, the magazine having a film slot adapted to register with the film slot of the kinetograph case, one side of said magazine slot being formed by a movable block, a spring normally pressing said block toward the other side of the slot to close the slot, said block having openings therein, and beveled pins, projecting from the bottom of the recess and adapted to engage in said openings to press the block back against the spring; the second men-

tioned end of the magazine base being similar in formation to the first mentioned end, the said means for holding the second mentioned end of the base embodying interengaging means on that end of the base and in the kinetograph case wall, and the first mentioned end of the base having also such interengaging means, so that the magazine base may be secured in the recess in a position turned end for end. 70

7. In combination, a kinetograph case having a wall with an exterior recess with an overhanging wall at one end, and with a film slot passing through the case wall from the recess, a film magazine having a base with an extended end adapted to fit under the overhanging recess wall and thereby be held in the recess, means for holding the other end of the base in the recess, the magazine having a film slot adapted to register with the film slot of the kinetograph case, one side of said magazine slot being formed by a movable block, a spring normally pressing said block toward the other side of the slot to close the slot, said block having openings therein, and beveled pins projecting from the bottom of the recess and adapted to engage in said openings to press the block back against the spring; the second mentioned end of the magazine base being similar in formation to the first mentioned end, the said means for holding the second mentioned end of the base embodying a screw set in the kinetograph case wall and the magazine base having screw threaded openings 90 one near each end engageable by the screw. 95

8. In combination, a kinetograph case having a wall with an exterior recess with an overhanging wall at one end; and with a film slot passing through the case wall from the recess, a film magazine having a base with an extended end adapted to fit under the overhanging recess wall and thereby be held in the recess, the magazine having a film slot adapted to register with the film slot of the case; the opposite end of the magazine base being similar in formation to the first mentioned end, means for holding the second mentioned end of the base in the recess embodying interengaging means on the end of the base and in the kinetograph case wall, and the first mentioned end of the base having also such interengaging means, so that the magazine base may be secured in the recess in a position turned end for end. 105

9. The combination of a kinetograph case having a magazine receiving seat, a magazine having a base adapted to be mounted on said seat, and complementary securing means on said base and seat, one of said complementary securing means being automatically set for manual manipulation when the parts are brought together. 115

10. The combination of a kinetograph case having a magazine receiving seat. a 120

magazine having a base adapted to be mounted on said seat, a screw receiving socket in one of said parts, and a resiliently mounted screw in the other on said parts adapted to be set for manual manipulation to engage said socket when the parts are assembled.

11. The combination of a kinetograph case having a magazine receiving seat, a magazine having a base adapted to be mounted on said seat, a screw receiving socket in said base,

and a spring mounted screw projecting from said seat and adapted to be set for manual manipulation to engage said socket when the parts are assembled.

In witness that I claim the foregoing I 15 have hereunto subscribed my name this 31st day of December 1919.

LLOYD BROWN.

Witness:

VIRGINIA BERINGER.
